UNITED STATES PATENT OFFICE.

HARRY V. BALL, OF CONCORD, MASSACHUSETTS, ASSIGNOR TO R. HOE & CO., INC., OF NEW YORK, N. Y., A CORPORATION OF NEW YORK.

PRINTING MACHINE.

Application filed July 25, 1925. Serial No. 45,971.

To all whom it may concern:

Be it known that I, HARRY V. BALL, a citizen of the United States, residing at Concord, county of Middlesex, and State of Massachusetts, have invented certain new and useful Improvements in Printing Machines, fully described and represented in the following specification and the accompanying drawings, forming a part of the same.

This invention relates to certain improvements in printing machine arrangements.

It is a special object of the present invention to provide an improved printing machine in which there is provided a plurality of printing and perfecting mechanism arranged in substantially the same plane with their cylinders parallel, the mechanisms being spaced apart sufficiently to permit turning bars and web guides to be located in the space these parts of the mechanisms being supported above a base or frame with a folder below the frame supported on the floor of the press room, and web roll supplies for the press located adjacent the folder so that the pressman has easy access to the parts of the press and can watch the run of the webs into the machine from the folder. It is a further object of the invention to produce an improved mechanism whereby the inking mechanism of the press can be regulated from the folder floor so that any required adjustments can be made without having to climb up to the inking mechanism, thus saving time and trouble in making adjustments.

With these and other objects not specifically referred to in view, the invention consists in certain novel parts, arrangements and combinations which will be described in connection with the accompanying drawings.

In these drawings,—

Figure 1 is a diagrammatic side elevation of a printing machine illustrating the invention;

Figure 2 is a detail sectional view on an enlarged scale of the inking mechanism and the means for adjusting it shown in Fig. 1;

Figure 3 is a broken side view, partly in section, the view being taken on the line 3-3 of Fig. 2 looking in the direction of the arrow;

Figure 4 is a plan view and Figure 5 an end view of a modified form of an inking mechanism and its adjusting devices which may be used within the invention, and

Figures 6 and 7 are details of the adjusting mechanism illustrated in Figs. 4 and 5.

Referring now to these drawings, the printing machine chosen to illustrate the invention includes two printing and perfecting mechanisms. It will be understood, however, that the invention is not to be restricted to a press of this capacity, but that the press can be enlarged within desired limits while retaining the important features of the present invention.

Such a press, however, will include a base or frame on which the printing couples are mounted low down with respect to the frame, and the sets of printing and perfecting couples will be spaced apart sufficiently to permit of the location in the space of the required guides and angle bars, these also being located low down with respect to the frame or base. The press will also include a foundation or floor on which the frame is supported, and on this floor below the frame will be positioned the folder and the web roll supplies for the printing mechanism, the web roll supplies being preferably located conveniently adjacent the folder.

In the particular construction shown the parts are supported on a floor 1 from which rise a suitable number of upright standards 2, 3, 4, which in turn support bases or frames 5, 6 on which are mounted the printing mechanisms and their inking devices. Beneath the printing mechanisms and underneath the frames 5, 6 are supported the web rolls for supplying the printing mechanisms, a running roll R and a spare roll S being shown for this purpose.

Located conveniently adjacent the web rolls and supported from the floor 1 is a framework 7 which supports the folder, diagrammatically indicated at 8. With this construction the pressman can readily regulate the web roll supply for marginal adjustment or any other desired reason, and a compact structure is provided. The folder frame 7 is united by a top frame 9 which is connected to the frames 5, 6, before referred to, these frames forming substantially a horizontal structure for supporting the press mechanisms and the web guides.

Web guides 10 and angle bars 11 are supported above the folder in the space between the printing mechanisms.

The printing mechanism shown includes a

form cylinders of which are marked 12, 13 and the impression cylinder 14, 15. The cylinders of these couples, as shown, are arranged in line and low down with respect to 5 their supporting frames, so as to be conveniently accessible. The mechanisms are a duplicate of each other and a description of one will suffice for both.

The form cylinders of each couple are 10 inked from a distributing roll 16 and form rolls 17 with the usual vibratory rolls 18. Ink is transferred to the distributing roll by the usual vibratory roll 19 which oscillates between the distributor 16 and the 15 fountain roll 20 which runs in an ink fountain 21 supported on an upright 22 rising from the base frame, as the frame 5.

It will be seen from the construction so far described that a very compact and easily 20 accessible press arrangement has been provided, one in which the pressman standing at the folder can readily regulate the web supply.

Where this press arrangement is employed 25 with the press mechanisms above the floor and the folder and rolls below, and where an ink fountain is employed for supplying ink to the form cylinders of the couples, it is desirable that provision be made so that the 30 pressman can adjust the ink supply from the floor without requiring him to climb up to the printing mechanism, and means are provided by the present invention by which the pressman may adjust the inking mechanism 35 from the folder floor. These means may vary somewhat in construction.

Referring first to mechanism shown in 40 Figs. 1 to 3 inclusive, the bottom of the fountain is provided with a flexible wall 41 shown in the form of a thin flexible blade marked 23, this blade being held in place in any suitable manner, as by being clamped against a shoulder 24 formed in the wall of the fountain and held in place by a clamping 45 strip 25 clamped in place by bolts 26.

This flexible wall or blade comes in contact with the fountain roll, and the proximity of the edge of the blade to the roll determines the amount of ink which the rolls 50 takes away from the fountain. In many instances, it is desirable to have more or less ink delivered to the roll at different points along its periphery and in accordance with the invention, these means are such that they 55 may be operated a considerable distance below the fountain. As shown, there are provided a plurality of adjusting screws 27, these screws extending widthwise of the blade, as shown in Fig. 3, and being arranged at close intervals along the flexible wall 23 so that the wall may be adjusted to and from the distributing roll at any desired point widthwise thereof. These adjusting screws are threaded through openings 60 28 formed in the wall of the fountain

and bear at their ends against the under side of the blade. By turning these adjusting screws the wall or blade 23 is adjusted to and from the roll. As shown, the adjusting screws pass through the bottom of the fountain at an angle. The outer end of each of the screws is provided with a mitre-gear 29. This mitre is in mesh with a mitre 30 on the end of a vertical rod 31 which extends downwardly through the supporting 75 frames to a position where it may be conveniently reached from the floor by the pressman, the rod being provided with a finger piece 32 by which it may be readily located. The rods 31 are or may be supported in any suitable manner, as in brackets 33 on the fountain wall and in brackets 34 secured to the supporting frame, and the gears are held in contact by upper and lower sets of collars 36, 37.

It will be understood, of course, that, as shown in Fig. 3, there is an operating rod 31 for each adjusting screw 27. In the best constructions certain of these rods are, as shown in Fig. 3, shorter than the others so 90 that the pressman may have no difficulty in reaching the desired rod.

In the construction shown in Figs. 2 and 3 it will be observed that the pressman has to walk the length of the roll in order to 95 operate all the adjusting screws. Under some circumstances it may be desirable to have all the operating rods at one side of the roll so that the pressman can reach any of the rods from one position, as, for instance, the former. A construction for effecting this is shown in Figs. 4 to 7 inclusive.

While the fountain construction shown in 105 Figs. 1 to 3 might be employed with the modified form of adjusting mechanism, under some circumstances a different fountain structure is desirable with the modified ink adjusting mechanism and such a modified fountain arrangement is shown in Figs. 4 to 110 7. Referring to these figures, the fountain will be supported on standards 22 similar to those heretofore referred to, the fountain being indicated by the numeral 40. The fountain will have rotating therein the roll 115 20 which will deliver ink to the parts similar to those already described. In the modified construction, however, the flexible plate or blade which controls the ink supply from the roll is not a part of the fountain bottom as heretofore described, but is shown as a thin plate 41 secured to a bar 42 in any suitable manner, as by bolts 42', this bar being mounted on a bracket 43 shown in dotted lines in Fig. 5, which bracket is supported from the standards 22, before referred to, this construction being duplicated on each side of the fountain. This plate is, as shown, mounted so as to engage the periphery of the fountain roll 20 somewhat 120 125 130

above its horizontal axis. This plate is, as stated, a flexible plate and means are provided for causing it to assume various positions with respect to the roll surfaces, these means being such that they can all be operated from one point at the side of the machine, as, for instance, closely adjacent the folder. While the specific character of these means may be somewhat varied, in the particular construction illustrated the frame 42 is provided with the desired number of vertical slots 44 in which work sliding pins 45, these pins preferably having rounded ends 46, 47. As shown in Fig. 7, by the movement of these pins up and down in the slots the bar is flexed toward and from the periphery of the roll. These pins or plungers are operated by means of rods 48, the operating ends of which are bevelled, as indicated at 49, the rods working in horizontal grooves 50 formed in the bar 42 before referred to. These rods are operated in one direction through connections herein-after described, and are returned by means of springs 51. To enable this spring 51 to function, the operating ends of the rods are reduced, as indicated at 52, and the spring 51 is positioned between a shoulder 53 on the rod and a shoulder 54 at the end of the grooves 50. These rods, it will be understood, are provided in the desired number to permit of the adjustment of the plate 41 at the desired points along the roll, and the operating means, furthermore, for these rods are so constructed and arranged that they can be operated from the folder level, that is, at any desired point below the ink fountain.

Referring to Fig. 6, the outer ends of the rods are reduced and take bearing in a bar 55 supported on an arm 56 of the bracket 43 secured to one of the standards 22, before referred to. The outer ends of the rods are rounded, as shown at 57, and these rounded ends engage the bevelled or inclined surfaces 58 formed on rods 59, these rods extending vertically below the frame 5 a desired distance to be readily accessible from the folder level. These operating rods 59 are mounted in any suitable manner. In the particular construction shown they have a threaded end 60 which passes through a leg 61 on the bar 55, before referred to. These rods at their lower ends are provided with a socket 62 to receive a wrench or other suitable operated tool by which they may be readily turned. If desired, of course, they may be provided with handles, such as the handle 32 before referred to. For convenience, these operating rods are arranged, as shown, in plan in Fig. 4, that is, arranged in sets of a small number of rods, each of these sets being offset from each other, as indicated at 63 in that figure. With this construction it will be observed

that no gearing is required for operating the rods, the coned ends of the operating rods riding upon the rounded ends of the rods 52, and the coned ends of these latter rods riding on the rounded ends of the plungers 45, thus a very simple and cheap construction is provided, but one which effectively accomplishes its functions.

While the invention has been shown and described in practical form, it will be understood that various changes may be made in the specific structure shown and described without departing from the invention.

What I claim is:

1. In a printing press arrangement, the combination of framing, a printing and perfecting mechanism with the cylinders in substantially horizontal alignment above the framing, a second printing and perfecting mechanism with the cylinders in substantially horizontal alignment above the framing, said mechanisms being spaced apart, turner bars and guides in the space, a folder below the framing, and roll supplies for the printing mechanisms below the framing on each side of the folder and adjacent thereto.

2. In a printing press arrangement, the combination of framing, a printing and perfecting mechanism with the cylinders in substantially horizontal alignment above the framing, a second printing and perfecting mechanism with the cylinders in substantially horizontal alignment above the framing, said mechanisms being spaced apart, turner bars and guides in the space, a folder below the framing, roll supplies for the printing mechanisms below the framing on each side of the folder and adjacent thereto, inking mechanism above the framing, and means accessible from the folder level below the framing for adjusting the inking mechanism.

3. In a printing press arrangement, the combination of framing, printing mechanism located above the framing, a folder located below the framing, inking mechanism above the framing, said inking mechanism including a fountain and a fountain roll, and means for adjusting the ink supply from the roll at a plurality of points widthwise thereof, said adjusting mechanism extending below the framing and being adjustable from the folder level.

4. In a printing press arrangement, the combination of framing, a printing and perfecting mechanism above the framing, a folder below the framing, an ink fountain above the framing, a fountain roll taking ink therefrom, a flexible ink regulating blade extending across the roll, a plurality of adjusting rods for flexing the blade, and a plurality of operating rods cooperating with the adjusting rods and extending downwardly below the framing and accessible from the folder level for adjusting the

blade at desired points widthwise of the roll.

5. In a printing press arrangement, the combination of framing, a printing and perfecting mechanism above the framing, a folder below the framing, an ink fountain above the framing, a fountain roll taking ink therefrom, a flexible ink regulating blade extending across the roll, a plurality of adjusting rods for flexing the blade, and a plurality of operating rods cooperating with the adjusting rods and extending downwardly below the framing and at one side of the fountain, said rods being accessible from the folder level.

6. In a printing press arrangement, the combination of framing, a printing and perfecting mechanism above the framing, an ink fountain above the framing, a flexible blade for regulating the ink taken from the fountain, a plurality of adjusting devices for flexing the blade, and a plurality of devices for operating the adjusting devices, said operating devices being located below the framing.

7. In a printing press arrangement, the combination of framing, a printing and perfecting mechanism above the framing, an ink fountain above the framing, a flexible blade for regulating the ink taken from the fountain, a plurality of adjusting devices along the blade for flexing it, and a plurality of devices for operating the adjusting devices, said operating devices being located to one side of the fountain and extending below the framing.

8. In a printing press arrangement, the combination of framing, a printing mechanism located above the framing, inking

mechanism above the framing, means for adjusting the ink delivered from the inking mechanism, and means extending below the framing for operating the adjusting mechanism.

9. In a printing press arrangement, the combination of framing, a printing mechanism located above the framing, an ink fountain above the framing, a flexible blade for regulating the ink from the fountain, plungers for flexing the blade, adjusting rods having sliding connection with the plungers, and operating rods having sliding connection with the adjusting rods, extending downwardly below the framing.

10. In a printing press arrangement, the combination of framing, a printing and perfecting mechanism arranged above the framing, inking mechanism for the printing mechanism, a folder below the framing, roll supplies for the printing mechanism below the framing, and means accessible from the folder level below the framing for adjusting the inking mechanism.

11. In a printing press arrangement, the combination of framing, a plurality of printing and perfecting mechanisms above the framing, inking mechanism for the printing mechanisms above the framing, a folder below the framing, roll supplies for the printing mechanisms below the framing, adjacent the folder, and adjusting mechanism operable from the folder level below the framing for adjusting the inking mechanism.

In testimony whereof, I have hereunto set my hand.

HARRY V. BALL.
